UNITED STATES PATENT OFFICE.

EDWARD H. DENNING, OF WILMINGTON, DELAWARE.

AMUSEMENT DEVICE.

Application filed October 16, 1923. Serial No. 668,893.

To all whom it may concern:

Be it known that I, EDWARD H. DENNING, a citizen of the United States, residing at Wilmington, in the county of New Castle 5 and State of Delaware, have invented new and useful Improvements in Amusement Devices, of which the following is a specification.

This invention relates to wheeled toys, 10 and contemplates a structure designed to afford young children considerable pleasure and amusement.

It is the object of the present invention to provide a wheeled platform upon which 15 is mounted a plurality of amusement apparatus, all of which are simultaneously put into operation by means actuated incident to the movement of the toy over the ground or surface.

20 More specifically stated, the invention embodies a wheeled platform on which is mounted apparatus representing a "merry-go-round" and a "Ferris wheel", both of which are operated from the axle of the 25 toy, while also mounted upon the platform is a "see-saw" and "swing" simultaneously operated with and from the said "merry-go-round" and "Ferris wheel", thus presenting a very pleasing appearance to the 30 child using the toy.

The nature and advantages of the invention will be better understood when the following detailed description is read in connection with the accompanying drawings, 35 the invention residing in the construction, combination and arrangement of parts as claimed.

In the drawings forming part of this application, like numerals of reference indicate similar parts in the several views, and wherein:

Figure 1 is a side elevation of the toy.
Figure 2 is a top plan view.

Figure 3 is a bottom plan view.

45 Referring to the drawings in detail, 10 indicates the platform mounted on front and rear wheels 11 and 12 respectively, these wheels being associated with axles 13 and 14 respectively. The wheeled platform is 50 adapted to be pushed over the ground or surface by means of a handle 15, so that the child using the toy will face the platform and thus view the various amusement devices which are put into operation as the 55 toy is wheeled over the surface.

Mounted upon the platform 12 adjacent

the front end thereof is an amusement device in the nature of a small merry-go-round, which device includes a vertically disposed shaft 16 which projects above and below the platform 10 and journaled in suitable bracket 17 which is secured to the underside of the platform. This apparatus also includes a sleeve like member 18 which is slipped over the upper end of 60 the shaft 16 and secured thereto for rotation therewith. Carried by this sleeve is a base 19 from which rises bars 20, the latter supporting the animal figures 21 and a canopy or top 22. The lower portion 70 of this shaft 16 supports a horizontally disposed pulley 23 utilized in the connection between the rear axle 14 and the amusement device just described. This connection includes a cable 24 which is trained over the 75 pulley 23, and also over one side of a duplex pulley 25, the lower run of the cable being trained over an idle pulley 26 journaled in a bracket 27 which depends from the underside of the platform 10. The duplex pulley 80 is fixed to the rear axle 14, and is of course arranged in a plane at a right angle to the pulley 23, the cable 24 being crossed as clearly shown in Figure 3. However, 85 by reason of this construction, it is manifest that when the axle 14 is rotated, simultaneous motion is imparted to the shaft 16 putting the merry-go-round into operation.

Also supported on the platform 10 adjacent the rear end thereof is an amusement apparatus in the nature of a small Ferris wheel, including a shaft 38 journaled in suitable brackets 29, the Ferris wheel proper being indicated at 30. This shaft 28 also 90 supports a pulley 31 over which and the other side of the duplex pulley 25 is trained a cable 32. The platform is provided with openings to receive the runs of the cable 32, so that when the toy is moved over the 95 ground or surface, the Ferris wheel is also put into operation simultaneously with the operation of the merry-go-round. Carried by the shaft 38 of this apparatus is a disk 33 with which the rod 34 is eccentrically 100 connected, the rod being also connected with a small swing 35 to actuate the latter incident to the operation of the Ferris wheel. The connection between this rod 34 and the swing is clearly indicated at 36 in 105 Figure 2. The swing 35 is suspended between spaced parallel supports 37, and piv-

oted between these supports as at 38. The disk 33 is arranged at one side of the Ferris wheel, while carried by the shaft 28 and arranged at the other side of this wheel is a 5 similar disk 39. Eccentrically connected to the disk 39 is a rod 40 which operates through an opening 41 in the platform 10, and which rod has its lower end connected with the adjacent extremity of a lever 42 10 fulcrumed at a point between its ends as at 43 for rocking movement. The lever is supported by a suitable bracket 44 depending from the underside of the platform 10, and has its other end connected with a vertically 15 disposed rod 45 which also operates through an opening 46 in the platform 10. This rod 45 projects above the platform and is terminally connected with the adjacent end of a see-saw 48, the connection between these 20 parts being indicated at 49, in Figures 1 and 2. The see-saw is pivoted between the spaced parallel guides 50 supported upon the platform 10. Consequently when the toy is moved over the surface, the merry-go-round and Ferris wheel are put into operation by reason of their connection with the 25 rear axle 14, while the swing and see-saw are simultaneously operated by reason of their connection with the shaft 28 forming 30 part of the Ferris wheel. As above stated, the child pushes the toy over the ground always facing the platform so that the simultaneous operation of the various amusement apparatus afford a very pleasing 35 appearance to the child giving him considerable pleasure and amusement. The toy is very simple in construction and can be manufactured and sold at a nominal cost.

While it is believed that from the fore-

going description, the nature and advantages of the invention will be readily apparent, I desire to have it understood that I do not limit myself to what is herein shown and described and that such changes may be resorted to when desired as fall within the scope of what is claimed. 40 45

Having thus described the invention, I claim:

1. In combination, a wheeled platform, a front and rear axle therefor, a duplex pulley carried by one of said axles, an amusement apparatus arranged above the platform and including a vertical shaft, a pulley carried by said shaft, a second amusement apparatus including a horizontal shaft 50 mounted for rotation, a pulley carried by the last mentioned shaft, cables trained over said duplex pulley, and the pulleys of the respective shafts whereby said amusement apparatus are operated when the toy is moved over the surface, and other amusement apparatus mounted on the platform and operated from the last mentioned shaft. 60

2. In combination, a wheeled platform, a plurality of amusement apparatus mounted thereon for rotation, means for rotating said apparatus simultaneously from one of the axles of said toy, one of said apparatus including a shaft, disks carried by the shaft, a swing mounted upon the platform, a see-saw mounted upon the platform, and means actuating the last mentioned devices with said disks for operating the same simultaneously with the operation of the said amusement apparatus. 65 70 75

In testimony whereof I affix my signature.

EDWARD H. DENNING.
